UNITED STATES PATENT OFFICE.

OTIS A. MYGATT, OF NEW YORK, N. Y.

ILLUMINATOR.

No. 823,621.

Specification of Letters Patent.

Patented June 19, 1906.

Application filed April 19, 1905. Serial No. 256,462.

To all whom it may concern:

Be it known that I, OTIS A. MYGATT, a citizen of the United States, residing at New York, in the county of New York and State of New York, have invented certain new and useful Improvements in Illuminators, of which the following is a specification.

This invention relates to composite illuminators having an incandescent electric lamp as a basis of illumination and a reflector co-operating therewith.

The object of the invention is to produce an illuminator composed of a lamp and reflector, as stated, by which light-rays from the filament of an incandescent electric lamp can be so directed and commingled as to illuminate a predetermined area, generally beneath the lamp, by means of the composite structure of lamp and reflector to a greater extent than could be done by the lamp alone and in such manner that the eyes of the user may be protected from radiant rays and the light softened and rendered agreeable to the eye.

The invention consists in the construction of the lamp-bulb and the reflector with special reference to their use in the combined or composite structure and in their combination in such structure. The lamp-bulb is provided with a frosted or similar partially reflective and partially diffusing surface over a portion of its body and a clear or transparent portion above the same. The reflector is constructed and arranged with such relation to both parts of the lamp as to give the desired result in the diffusion, distribution, and commingling of the light-rays.

Incandescent lamp-bulbs are generally made of pear shape with the filament of a single or double loop form and about concentric with the curved large end of the bulb, because such bulbs have demonstrated their superiority in the matters of cost, durability, and general adaptability.

Lamp-bulbs have been frosted and have been varnished in whole or in part with the object of softening the light-rays passing through the frosted surface. So far as I am aware no special attempt has been made prior to my invention to reflect the reflected rays from the surface of frosted glass in determined directions and to commingle such rays with radiant rays and reflected rays controlled as to their direction by reflecting-surfaces.

In the drawings intended to illustrate the general features of my invention, Figure 1 is

a side elevation of an incandescent lamp-bulb having a partially-frosted or ground surface and a partial surface of clear glass and a reflector of prismatic glass shown in section, 60 the course of some light-rays being indicated. Fig. 2 is a side elevation of a lamp-bulb and a prismatic reflector, the entire surface of the bulb which is not covered by the reflector being ground or frosted. Fig. 3 is a side elevation of a lamp-bulb and reflector of different form, showing an uncovered transparent portion of the bulb under the reflector. Fig. 4 is a side elevation of a lamp-bulb and reflector of different form, the bulb being frosted in 70 scallops. Fig. 5 is a side elevation of a lamp-bulb with its frosted portion carried within the reflector and a reflector shown in section and indicating the course of some light-rays. Figs. 6, 7, and 8 are illustrative comparative 75 diagrams showing outlines of fields of illumination under different conditions, as will be explained.

Incandescent electric lamps as generally constructed throw the strongest light side-wise and the weakest light in upward and downward direction. As these lamps are most frequently hung as pendants and the light is mostly desired in downward direction or at about forty-five degrees from the vertical, it has been quite common to use a reflector with such a lamp to reflect the light downwardly. Reflectors of metal or silvered glass placed above the lamp can be used as elements in my combination; but as such reflectors cut off all the light and leave the ceiling dark I prefer to use reflectors of prismatic glass which can be constructed to reflect as much as eighty-five per cent. of the light rays, but pass some rays which illuminate 95 the outside of the reflector and the wall or space above the same. Reflectors of porcelain or opal glass permit the passage of some light-rays and reflect some of the rays, but are not efficient in directing light in definite 100 directions and in definite quantities.

In all common forms of reflector considerable light is absorbed. For my purpose prismatic glass is preferred as being least absorbent of light-rays.

Referring now to Fig. 1, let A represent an incandescent lamp-bulb transparent at its upper part, and B indicates the ground or frosted lower part of said bulb. The frosted surface may be obtained by grinding, by etching, or by the use of varnish known in this art.

The effect of the frosted or ground semi-

opaque surface on the glass is to permit some of the light to pass through the glass, but in a diffused or softened condition, and all direct view of the filament through the ground surface is cut off. By grinding or opaques the lower part of the incandescent lamp-bulb to a plane somewhat higher than the widest diameter of the bulb and hanging a "flared-out" deflector over the bulb, so that its lower edge will extend below the upper edge of the frosting, all direct view of the filament may be cut off either by the reflector or the frosting. The direct light-rays through the transparent part of the bulb reach the reflector as usual. Some light-rays are reflected by the frosted surface of the bulb, and these may be rereflected by the reflector either through the bulb or alongside thereof, as may be calculated.

The reflector C, Fig. 1, is of clear glass, having a prismatic outer surface, and is of the general character described in United States Patent No. 687,848, December 3, 1901. The radial prisms on the outer surface of this reflector are of the character frequently termed "double" reflecting prisms. To be most efficient as reflectors, the prisms should be arranged with their flat faces about forty-five degrees from radial lines emanating from the source of light.

A filament of the usual and preferred form throws out rays of light from all parts of its surface. For the present I will only consider light-rays as emanating from the center of the filament. Referring to Fig. 1, let us suppose the ray $c\ d$ to radiate from the center c to the reflective surface d of the reflector. At d this ray is reflected back in a line nearly parallel with the line $c\ d$, and after passing through the frosted surface B of the bulb the ray emerges in the direction e , but is softened and diffused by passing through the frosted glass. Of course there are direct rays which pass in the direction $c\ e$ and intermingle with the reflected rays.

The frosted surface is not only a diffusing, but a reflecting, surface. While the larger portion of the direct rays pass through the semi-opaque surface, some rays are reflected thereby. Let us consider the course of such a ray, as $c\ f$. That part of the ray which is reflected at f is thrown back toward g on the reflector. The form of the reflector determines the subsequent course of the light-ray. The reflector may be of such form as to throw such a reflected ray in the direction h . Such a reflected ray is much softer than a radiant ray which has been merely reflected from the reflector C—as, for instance, the ray indicated at $c\ i\ k$.

I will now consider some of the light-rays thrown out from near the ends of the filament, those rays from near the upper ends of the filament being less brilliant. Thus, $l\ m\ n$ indicate the course of a light-ray, the direction

of the ray from m to n depending on the form of the reflector as well as on the inclination of its prisms.

The reflector C', Fig. 2, is of a form to concentrate the reflected rays downwardly in a large degree. The frosted surface B' in the same figure is extended up as far as the lower edge of reflector C', so that in most positions no direct rays from the filament can reach the eye. The frosted surface B' may act as a reflector for as much as one-half the light which reaches it, and light so reflected is in a different condition from that of light reflected from ordinary polished surfaces, the reflected rays being also softened. By increasing or diminishing the area of the frosted surface of the lamp more or less of the total amount of light may be reflected and softened thereby. By changing the character of the prisms on reflector C more or less of the light may be reflected by said reflector, the rays not reflected passing through the reflector. By changing the form of the reflector C the reflected light-rays may be more or less concentrated. By varying the distance between the reflector and the bulb the reflected light-rays are projected from different parts of the reflector and the whole combination may be changed. Thus in Fig. 5 the direct ray o from one side of the filament encounters the reflector C^2 at p and is reflected downward toward r . The ray o' is reflected in part from the frosted surface B^2 , reaches the reflector at p' , and is directed in its softened condition to r' . The direct ray o^2 , softened by passing through the frosted surface B^2 , reaches r^2 . We have thus three different kinds or qualities of light about at the point r , and of course the same conditions exist actually at the point r' . Now if the reflector C^2 be lifted, as indicated in the broken section at the left, (dotted lines,) Fig. 5, then the lines $p\ p'$ will strike a different part of the reflector and by the form of the reflector their direction will be changed, substantially as indicated in dotted lines.

Referring again to Fig. 5, let us follow light-rays from the point s on the filament. The direct ray $s\ s'$ passes over the frosted surface on the bulb and under the reflector, but in such a direction that it is largely lost in space. The ray $s\ s^2$ from the same point is in part reflected back to s^3 on the reflector and is then thrown downwardly toward s^4 in a much more useful direction and in softened condition.

From the above it will be known that my combination of partly-frosted bulb and movable reflector affords very wide latitude in the control of the illuminating properties and qualities of an incandescent lamp. A lamp-bulb is very cheaply frosted by etching, and a greater or less proportion of the bulb may be frosted according to the character of illumination desired. The reflector can be made of

such form as to direct the reflected and the rereflected rays in almost any direction and to modify the character of the rays by directing them through the frosted surface or otherwise, and the rereflected rays are invariably softened, as are the rays which pass through the frosted glass.

The arrows in Fig. 3 and Fig. 4 show the general or paramount direction of the reflected light-rays due to such general forms of reflector, arranged in about the illustrated relation to a lamp-bulb of the form and character shown. The flaring reflector of Fig. 3 can be made to direct nearly all the reflected light-rays outwardly between the lamp-bulb and reflector and very few reflected rays will be returned through the lamp. Under such circumstances the filament of the lamp will endure much longer than in the form shown in Fig. 2, by which the rays are concentrated downward. Thus my invention may be so modified as to conserve the life of the lamp as long as possible.

In the diagram Fig. 6 the dotted line 1 indicates the outline of the distribution of light about a transparent glass lamp of thirty-two-candle power, and the full line 2 indicates the distribution of the same lamp with a reflector of the form shown in Fig. 5 applied thereto. In Fig. 7 the dotted line 3 indicates the outline of distribution from the same power-lamp, lower half frosted, and the full line indicates the same combined with the reflector of Fig. 6.

Fig. 8 shows lines 2 and 4 superposed, illustrating clearly the differences resulting from a change in the elements constituting the combination of my improved illuminator.

I have referred to the upper and lower ends 40 of the bulb, such being the usual operative portion of incandescent lamps of the character illustrated, but it should be understood that the position of the illuminator may be changed.

It has been common to produce reflectors for incandescent electric lamps by silvering a part of the surface of the lamp. Owing to the concentration of heat in such cases, such a lamp has but about half the life of an un-silvered lamp. Reflectors have also been made of metal placed close to the lamp, and for a like reason these lamps are also short-lived. It has been proposed to make lamp-bulbs with concave outer surface, as in Fig. 52 of British Patent No. 23,111 of 1895. From the collapse of hundreds of bulbs of concave construction under vacuum pressure I am convinced that such construction is not practical. My reflector heretofore described 60 being separate from and held at a little distance from the lamp-bulb does not concen-

trate heat to a destructive degree, and bulbs will last as long in the combination with the reflector as without a reflector. This is not true of any reflector which is in contact with the bulb, so far as I know, unless provision is made for ventilation between the bulb and reflector.

What I claim is—

1. The combination, in an illuminator, of 70 an incandescent lamp-bulb having its upper portion transparent and its lower portion frosted, and a separate reflector a little removed from said bulb, and surrounding the clear portion thereof, leaving the frosted portion of the bulb projecting below the bottom of the reflector.

2. The combination, in an illuminator, of 80 an incandescent lamp-bulb and a little removed from said bulb frosted at its lower end and transparent above the frosting, and a separate and removable reflector of prismatic glass surrounding the clear end of the bulb and flaring outward beyond the widest part of the bulb.

3. The combination, in an illuminator, of 85 an incandescent lamp-bulb frosted at its lower end and transparent above the frosting, and a separate and removable reflector of prismatic glass, having its outer surface substantially covered with double reflecting-prisms, arranged about the transparent end of the bulb and a little removed from said bulb and projecting outward beyond the greatest diameter of the bulb.

4. The combination, in an illuminator, of 90 an electric lamp-bulb having its lower part frosted and its upper part transparent, and a prismatic glass reflector surrounding the clear part of said bulb and a little removed 100 therefrom; said reflector having its outer surface substantially covered with double reflecting-prisms arranged radially; the lower edge of the reflector flaring beyond the largest diameter of the lamp and terminating above 105 the plane of the frosted portion of the bulb.

5. The combination, in an illuminator, of 110 an incandescent lamp-bulb frosted at its lower end and transparent above the frosting, and a separate and removable reflector of prismatic glass surrounding the clear end of the bulb and a little removed therefrom, said reflector flaring outwardly beyond the widest part of the lamp-bulb, so as to direct the majority of the reflected light-rays away from 115 the lamp-bulb.

In testimony whereof I affix my signature in presence of two witnesses.

OTIS A. MYGATT.
